UNITED STATES PATENT OFFICE

WILLIAM SCHAAKE, OF PITTSBURGH, PENNSYLVANIA, ASSIGNOR TO WESTINGHOUSE ELECTRIC & MANUFACTURING COMPANY, A CORPORATION OF PENNSYLVANIA

PANTOGRAPH COLLECTOR

Application filed October 20, 1930. Serial No. 489,874.

My invention relates to current collectors for electrically propelled vehicles and particularly to current collectors of the pantograph type.

8 An object of my invention, generally stated, is to provide an improved pantograph collector which shall be simple and efficient in operation and which may be readily and economically manufactured.

10 Another object of my invention is to provide for varying the pressure between a current-collecting member and a trolley conductor.

15 Another object of my invention is to provide a pantograph structure which shall be suitable for supporting one or more current-collecting shoes.

20 For a fuller understanding of the nature and objects of the invention, reference may be had to the following detailed description, taken in conjunction with the accompanying drawings, in which:

25 Figure 1 is a plan view of a part of a pantograph collector, constructed in accordance with my invention.

Fig. 2 is a view, in side elevation, of the structure shown in Fig. 1.

Fig. 3 is an enlarged view, in side elevation, of an adjustable cam utilized in the pantograph structure, and

30 Fig. 4 is a view, in end elevation, of the adjustable cam shown in Fig. 3.

Referring to the drawings, the apparatus shown comprises a supporting frame 10 which may be constructed of angle-iron bars. A pantograph frame 11, which may be constructed of metal tubing, is supported on two shafts 12 which are rotatably mounted on the frame 10 by means of bearing members 13.

35 The pantograph frame may be of any standard construction and, since this form of mechanism is well known, a detailed description thereof will not be given.

40 As illustrated, two current-collecting shoes 14 are carried by the pantograph frame 11 which may be extended to raise the collecting shoes into contact with an overhead conductor when it is desired to operate the vehicle, or lowered to the position shown in the drawings when the vehicle is not in service.

In the preferred form of my invention, the pantograph frame 11 is raised by the tensioned coil springs 15 and lowered by means of air operated mechanisms 18. The springs are so connected to the shafts 12 that they will rotate the shafts in one direction, and the air engines are disposed to oppose the springs.

45 As illustrated, four main springs 15 are provided for raising the pantograph frame 11. Two of the springs 15 are connected to each of the shafts 12 by means of cams 16 which are rigidly mounted on the shafts 12 in such manner that the springs 15 rotate the shafts 12 in a direction to raise the pantograph frame 11. As shown, one end of each of the springs 15 is connected to the supporting frame 10 by means of a bolt 17.

50 Two air engines 18 are provided for lowering the pantograph frame 11. The engines 18 may be of any standard construction and will not be described in detail. They are provided with pistons which are operated by air pressure and are so connected to the shafts 12, by means of lever arms 19 (see Fig. 2), that they will rotate the shafts in a direction to lower the frame 11 when air pressure is applied to the pistons.

55 In order that the pantograph collector may be suitable for use under different operating conditions, it is desirable that either one or two current-collecting shoes may be provided. It will be understood that, on account of the difference in the weight carried by the pantograph frame when two shoes are provided in place of one, more force is required to raise the pantograph frame and to maintain the proper contact pressure between the collecting shoes and the trolley conductor.

60 With a view to providing the additional force required to raise the pantograph frame, when it is equipped with two collecting shoes, two auxiliary springs 21 are provided. One end of each of the springs 21 is connected to the supporting frame 10 by a bolt 22, while the other end is connected to one of the shafts 12 by means of an adjustable cam 23. The spring fits into a groove 35 on the cam and is connected to a lug 36.

65 Referring to Figs. 3 and 4 of the drawings, it will be seen that the position of the

66

70

75

80

85

90

95

100

cam 23 on the shaft 12 may be changed by means of two set screws 24. It will be observed that a collar 25, which is keyed to the shaft 12 by two pins 26, is provided with a downwardly extending arm 27 and also an upwardly extending arm 28. The cam 23 is rotatably mounted on the shaft 12 and is retained on the shaft by a ring 29 which is keyed to the shaft 12 by a pin 31. The cam 10 23 is provided with a downwardly extending arm 32 which is disposed between two outwardly projecting lugs 33 on the arm 27 of the collar 25. The set screws 24 are mounted in the lugs 33 to engage the arm 32 of the cam 23. In this manner, the position of the cam 23 on the shaft 12 may be changed by adjusting the set screws 24.

As shown in Fig. 2, equalizing rods 34 are provided to ensure that the two shafts 12 shall be rotated to the same degree. One end of the rod 34 is connected to the arm 28 of the collar 25, and the other end is connected to the lever arm 19 which is actuated by the air cylinder 18. One equalizing rod is provided at each side of the pantograph frame.

It will be seen that the force exerted by the auxiliary springs 21, tending to raise the pantograph frame and also the pressure of the collecting shoes 14 against the overhead conductor, may be governed by changing the position of the cams 23 on the shafts 12 by means of the set screws 24. Changing the position of the cams 23 varies the tension of the springs 21 and also varies the moment 35 of the torque applied by the springs to rotate the shafts 12.

When a change is made from one collecting shoe to two shoes, or vice versa, the cams 23 may be readily adjusted to give the necessary actuating force for raising the pantograph frame and to maintain the desired contact pressure against the trolley conductor. It is not necessary to vary the tension of the main springs 15 when changing the number 45 of collecting shoes, thereby greatly simplifying the operations required.

Since numerous changes may be made in the above-described construction, and different embodiments of the invention may be made without departing from the scope thereof, it is desired that all matter contained in the foregoing description or shown in the accompanying drawings shall be interpreted as illustrative and not in a limiting sense.

I claim as my invention:

1. In a pantograph collector, in combination, a supporting frame, a plurality of rotatable shafts carried by said frame, a pantograph frame mounted upon said shafts, a collecting shoe carried by the pantograph frame, means biased by springs for raising the pantograph frame, means actuated by fluid pressure to lower the pantograph frame, and adjustable-cam means for varying the

force exerted by the spring-biased means for raising the pantograph frame.

2. In a pantograph trolley for collecting current from a trolley conductor, in combination, a pantograph frame, a plurality of shafts for supporting said frame and for actuating the same when rotated, a plurality of cams mounted upon and rotating with said shafts, a plurality of springs connected to the cams and disposed to rotate the shafts to actuate the pantograph frame in one direction, means actuated by fluid pressure to rotate the shafts to actuate the pantograph frame in the opposite direction, and means for adjusting the position of the cams on the shafts for varying the tension of said springs to vary the force exerted on the pantograph frame.

3. In a pantograph trolley for collecting current from a trolley conductor, in combination, a pantograph frame, a plurality of shafts for supporting said frame and for actuating the same when rotated, a plurality of cams mounted upon and rotating with said shafts, a plurality of springs connected to the cams and disposed to rotate the shafts to raise the pantograph frame, means actuated by fluid pressure to rotate the shafts to lower the pantograph frame, and means for varying the position of the cams on the shafts to vary the force applied by the springs.

4. In a pantograph trolley for collecting current from a trolley conductor, in combination, a pantograph frame, a collecting shoe carried by the frame and disposed to make contact with the trolley conductor, a plurality of shafts for supporting said frame and for actuating the same when rotated, a plurality of cams mounted upon and rotating with said shafts, a plurality of springs connected to the cams and disposed to rotate the shafts to raise the collecting shoe into engagement with the trolley conductor, a plurality of mechanisms actuated by fluid pressure to rotate the shafts to lower the collecting shoe, and means for adjusting the position of certain of said cams on the shafts to change the tension of certain of said springs, thereby varying the pressure between the collecting shoe and the trolley conductor.

5. A pantograph trolley for collecting current from a trolley conductor comprising a supporting frame, a pantograph frame, spring means for raising the frame, fluid-pressure means for lowering the frame, and means for varying the force exerted by the spring means, whereby the pantograph frame may be utilized for supporting one or a plurality of current-collecting shoes.

6. A pantograph trolley for collecting current from a trolley conductor comprising a supporting frame, a pantograph frame, a plurality of rotatable shafts for supporting the pantograph frame, a plurality of cams mounted upon and rotating with said shafts,

a plurality of springs connected to the cams and disposed to raise the pantograph frame, mechanisms actuated by fluid-pressure to lower the pantograph frame, and means for changing the position of certain of said cams 5 on the shaft to vary the force exerted by certain of said springs, whereby the pantograph frame may be utilized to support one or a plurality of collecting shoes.

7. In a pantograph trolley for collecting 10 current from a trolley conductor, in combination, a pantograph frame, a plurality of rotatable shafts for supporting the pantograph frame, a plurality of cams mounted upon and rotating with the shafts, a plurality 15 of springs connected to the cams and disposed to apply a torque to rotate the shafts, and means for adjusting the position of the cams on the shafts to vary the torque applied by the springs.

20 In testimony whereof, I have hereunto subscribed my name this 15th day of October, 1930.

WILLIAM SCHAAKE.
